UNITED STATES PATENT OFFICE.

EDWARD AUGUST PETERS, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

AUTOMATIC MUSICAL INSTRUMENT.

1,286,402.

Specification of Letters Patent.

Patented Dec. 3, 1918.

Application filed August 7, 1914. Serial No. 855,557.

To all whom it may concern:

Be it known that I, EDWARD AUGUST PETERS, a citizen of the United States, residing at North Tonawanda, in the county of 5 Niagara and State of New York, have invented new and useful Improvements in Automatic Musical Instruments, of which the following is a specification.

This invention relates to pianos and similar instruments having one or more pipe-stops, such as violin or flute pipes, or other auxiliary sound-producing devices.

The piano-action is commonly played automatically by striker pneumatics connected 15 with a suction wind chest, while the stops are connected with a separate pressure chest containing valves or pallets controlled by a series of motor pneumatics, such instruments being so organized that the piano can be 20 played alone or in concert with one or more of the stops.

It is the main object of my invention to simplify the connections between the piano and stop-sections of the instrument, in order 25 to reduce its cost of manufacture and facilitate the assemblage and repair of the parts.

A further object is to so construct the wind chest of the piano action that it is adaptable to ordinary automatic pianos 30 without such pipe-stops, as well as pianos having stops.

In the accompanying drawings: Figure 1 is a transverse vertical section of a piano embodying the invention. Fig. 2 is a fragmentary rear view of the main wind chest, showing some of the striker-pneumatics in section. Fig. 3 is a transverse section on line 35 3—3, Fig. 2. Fig. 4 is a vertical longitudinal section on line 4—4, Fig. 3.

Similar characters of reference indicate 40 corresponding parts throughout the several views.

1 indicates the hammers of the piano-action which latter may be of any ordinary 45 construction and constitutes the main sound producing parts of the instrument, 2 indicates the usual keys for playing the piano manually, and 3 the abstracts which are engaged at their lower ends by the keys.

4 indicates the motor or striker-pneumatics 50 for playing the piano automatically. In the construction shown, these pneumatics are secured to the rear side of the main or piano-action wind chest 5, their upper boards be-

ing fixed and their lower movable boards 55 having arms 6 which engage vertically-adjustable buttons 7 carried by lugs 8 projecting from the front sides of the abstracts 3. The striker-pneumatics are arranged in a number of tiers, and in staggered relation 60 for compactness. The lugs 8 of adjacent abstracts are arranged at different elevations corresponding to the respective pneumatics, as best shown in Figs. 3 and 4. The upward movement of the movable board of each 65 striker pneumatic is limited by an adjustable stop-button 9 carried by its upper fixed board.

The main or suction wind chest 5 contains a pneumatic action of any suitable construction which controls the striker-pneumatics 4. It has the usual suction chamber 10 connected with the customary pump or main suction bellows 11 which is operated by an electric or other suitable motor 12. As is 70 common in such pneumatic actions, each striker-pneumatic is connected by a passage 13 with a valve-chamber 14. This chamber is connected by a port 15 with the main suction-chamber 10 and by a port 16 with the outer atmosphere, these ports being controlled by the usual suction and flushing valves 17 and 18, both mounted on a valve-stem 19 actuated by the usual primary pneumatic 20. To this primary pneumatic leads 75 the duct 21 forming a continuation of the tube 22 connected with a duct of the tracker board 23. As is well understood, when a perforation of the music sheet registers with a tracker duct, the valves 17 and 18 are 80 shifted to the proper position to collapse the corresponding striker-pneumatic and operate the companion piano-hammer, while when the perforation breaks register with said duct, the valves are shifted in the opposite direction by a spring 24, flushing the 85 striker pneumatic and allowing it to expand.

25 indicates the auxiliary or pressure-chest of the instrument with which are combined a number of stops or auxiliary sound 90 producing devices such as violin and flute pipes 26 and 27. This chest and the devices for controlling the admission of compressed air to the pipes may be of any suitable or well known construction. In the example 100 shown, this chest is located on the rear side of the piano-case and is of ordinary construction. 28 indicates the pressure cham-

ber connected with the usual pressure-bellow 29 by the tube 30, and 31 one of the valves or spring-pressed pallets arranged in said chamber and controlling the passage 32 5 leading to the corresponding pair of violin and flute pipes 26, 27. 33 indicates the customary stop-slides which may be operated by any suitable means.

Each of the pallets 31 is controlled by a 10 motor-pneumatic 34 preferably applied to the back of the pressure-chest 25 and operating to open said pallet through a rod 35 guided in said chest. The chamber of each of these pallet-pneumatics is connected by a 15 tube or conduit 36 with the chamber of the striker-pneumatic representing the corresponding tone. In the preferred construction illustrated in the drawings, the lower end of this tube is connected with a channel 20 37 leading to the interior of the pallet-pneumatic, while its upper end is attached to a nozzle or short-tube 38 secured to and passing through the upper fixed board of the striker pneumatic. This tube forms an auxiliary passage independent of the main passage 13 of said striker pneumatic.

By pneumatically connecting the pallet-pneumatics with the striker-pneumatics, the former are obviously collapsed and inflated 30 in unison with the latter, being exhausted and flushed through the striker pneumatics and the valve chambers 14, thus dispensing with separate valve mechanism for exhausting and flushing the pallet-pneumatics and 35 correspondingly simplifying and reducing

the cost of the instrument and facilitating the assemblage and repair of the parts.

This construction has the further advantage that the main or piano action chest may 40 without reconstruction be used in automatic pianos having no pipe stops, as well as those supplied with stops, it being only necessary in the former case to plug the nozzles 38. The piano-action chest can thus be manufactured as a standard one applicable to a 45 variety of instruments of this character.

I claim as my invention:

In an instrument of the character described, the combination of a main wind chest containing a suction chamber, a valve 50 chamber connected with the atmosphere by a flushing port and with said suction chamber by an exhaust port, valve mechanism controlling said ports, a main pneumatic having its fixed board provided with independent main and auxiliary passages, said main passage connecting the pneumatic with said valve chamber, an auxiliary wind chest, a controlling valve in the last-named chest, an auxiliary pneumatic for actuating said 55 controlling valve, and a conduit connected at one end with the chamber of said auxiliary pneumatic and at its other end to the auxiliary passage of said main pneumatic.

Witness my hand this 3rd day of August, 60 1914.

EDWARD AUGUST PETERS.
